UNITED STATES PATENT OFFICE.

SAMUEL S. CHILDS, OF BERNARDSVILLE, NEW JERSEY.

SPRING-WHEEL.

No. 878,937.

Specification of Letters Patent.

Patented Feb. 11, 1908.

Application filed February 15, 1907. Serial No. 357,515.

To all whom it may concern:

Be it known that I, SAMUEL S. CHILDS, a citizen of the United States, residing at Bernardsville, in the county of Somerset and State 5 of New Jersey, have invented certain new and useful Improvements in Spring-Wheels; and I do hereby declare the following to be a full, clear, and exact description of the invention, such as will enable others skilled in 10 the art to which it appertains to make and use the same, reference being had to the accompanying drawings, and to letters of reference marked thereon, which form a part of this specification.

15 This invention relates to an improved vehicle wheel that comprises a body portion having a felly, and having a rim surrounding the felly at a distance therefrom.

The invention is designed to provide spring 20 elements or bumpers between the felly and the rim, these spring elements being adapted to be made to stand a radial compression, and also be adapted to transmit motion circumferentially between the felly and the rim.

25 The spring elements of this device are preferably made in the form of blocks, of rubber or similar compressible material that is at the same time elastic or resilient.

The invention is illustrated in the accompanying drawings, in which—

Figure 1 is a side view of a portion of a wheel made up according to my present ideas. Fig. 2 is a longitudinal section through one of the spring elements or bumpers, and Fig. 3 is a section on line 3, 3, in Fig. 2.

The body portion is made up of the hub 10, the spokes 11, and the felly 12. Surrounding the felly, and at a distance therefrom, is 30 the rim 13 which is provided with any well known form of tire 14. At suitable points on the inside of the rim and secured by rivets or screws 15, are the circular plates 16, which are screw-threaded on their peripheries. Opposed to each plate 16 is a cup 17 having a marginal rim 18, and a central boss 19, this boss being screw-threaded. Suitable bolts 20 pass through the felly and are screwed into the boss 19, being held against removal 45 by the heads 21. These cups 17 are dis-

posed on the felly so as to be opposite the plates 16. In each cup 17 is placed a block 22 which is made of rubber or any compound that will give resiliency to the block, and there is a perforation 23 in the block to fit 55 over the boss 19. A ring 24 is arranged to slide on the block 23, and these rings 24 are slid back on each block, and the assembling of the wheel is permitted by reason of these rings passing in under the plates 16. 60

When the rings 24 which are internally screw-threaded on the upper end, are screwed up on the plates 16, the blocks 22 are held against any lateral displacement, and at the same time there is enough space between the 65 inner edge of any of the rings 24 and the outer edge of the rims 18 to permit sufficient resiliency to the wheel. Small washers of leather, or similar material 25 can be placed under the cups 17 to prevent tilting of the 70 cups, and thereby avoiding undue strain on the bolts 20. It will also be seen that any circumferential strain on the wheel will be transmitted to the blocks, and when the blocks have been submitted to this circumferential strain, they will act in unison to 75 transmit power from the felly to the rim, or vice versa. The shape of the cups and the rings, and of the resilient blocks, can be altered as to their shape and ornamentation 80 to suit the ideas of the constructor.

Having thus described my invention, what I claim is:

1. In a spring wheel, a resilient block, a cup on one end of the block having a marginal flange to embrace the block, means for securing the block to the felly of a wheel, a screw-threaded plate, a ring sliding on the block and having an internal screw-thread on one end to engage the plate, and means 85 for attaching the plate to the rim of a vehicle.

2. In a spring wheel, a resilient block, a cup embracing the block and secured to the felly of a wheel, a plate adapted to be secured to the rim of a wheel, and a ring sliding on 95 the block and adapted to be detachably secured to the plate, whereby when the ring is detached from the plate the block can be removed between the felly and the rim.

3. In a spring wheel, a body portion hav- 100

ing a felly, a rim surrounding the felly at a distance therefrom, a cup secured to the felly having a marginal flange and a central boss, a resilient block having a central perforation, 5 a plate secured to the rim, a sleeve sliding on the block, and means for detachably securing the sleeve to the plate.

In testimony, that I claim the foregoing, I have hereunto set my hand this twelfth day of February 1907.

SAMUEL S. CHILDS.
